DETERGENT COMPOSITION WITH IMPROVED
BLEACHING EFFICIENCY

Jean Lucien Hirtz, Suresnes, and Gilles Noiriel, Puteaux, France, assignors, by mesne assignments, to Colgate-Palmolive Company, New York, N.Y., a corporation of Delaware

6 Claims. (Cl. 252-99)

The present invention relates to an improved method of laundering at the boil and to detergent compositions therefor having enhanced bleaching efficiency.

Detergent compositions previously proposed for laundering at the boil are complex mixtures comprising one or several synthetic detergents, such as an alkyl aryl sulfonate, various mineral salts (most often alkaline phosphates) and substances for preventing redeposition of soil on washed goods once the soil is removed therefrom. In addition, it has also been proposed that such compositions contain optical bleaching agents, perfumes, anti-corrosion agents and the like. On some occasions, soap is proposed for use in place of the above-indicated synthetic detergents.

However, it has long been recognized that under normal washing conditions such detergent mixtures are not always effective to remove all soils from laundry. This is because some soils are stains caused by various coloring matter which are fixed on textile fibers by a mechanism similar to dyeing. Unfortunately this coloring is very often encountered as, for example, in the stains caused by wine, tea, coffee, cocoa, fruit, lipstick and the like.

In order to remove these dye-like stains, it is generally necessary to perform an oxidizing treatment. For this reason, a large number of detergent compositions contain, in addition to the previously mentioned components, a certain amount of a persalt bleaching agent such as a water-soluble perborate. The perborate most generally employed is sodium perborate, in amounts of between 5 and 30% by weight of the detergent mixture.

However, the perborate not only oxidizes the coloring matter contained in the material to be laundered, but also decomposes thereby releasing gaseous oxygen. This liberation of gaseous oxygen is highly wasteful and results in a loss of a substantial amount of perborate. Since the latter is an expensive material, this loss is highly significant. Moreover, heavy metals, even those contained as impurities in water or in washing containers, catalyze the decomposition of the perborate.

In order to overcome this undesirable catalytic action, it has been proposed to include certain strong sequestering agents such as ethylene diamine tetra-acetic acid (EDTA) or its salts, and di-ethylene triamine penta-acetic acid (DTPA) or its salts, in detergent compositions containing sodium perborate. However, in the course of our research, it has been discovered that although the presence of these sequestering agents diminishes catalytic decomposition of the perborate, such presence also weakens the bleaching power thereof.

In accordance with the present invention, a stable, substantially dry perborate-containing detergent composition comprises a water-soluble organic detergent, a water-soluble perborate, a water-soluble inorganic copper salt, and a sequestering agent stable in the presence of said perborate and which forms a complex with copper having a dissociation constant the common logarithm of which is between about -11 and -15, said copper salt and sequestering agent being present in amounts sufficient to enhance the bleaching action of the perborate at the boil.

2

In the practice of this invention, the term "substantially dry" denotes a flowable particulate apparently dry solid containing up to 12 to 16% moisture and preferably 12½-15½ % moisture.

- 5 The dissociation constants indicated above are determined at the conditions most generally accepted in the literature for determinations of this kind. These conditions are a temperature of from 20 to 30 degrees C., and an ionic strength of 0.1, using an electrolyte consisting of potassium chloride.
- 10 It is to be understood that these conditions of measurement are not those encountered during the washing, but represent a standard for indicating and determining the appropriate dissociation constants which will enable the skilled worker to choose the desired sequestering agents for the detergent compositions of this invention. In this regard, it should be noted that the optimum concentration of copper ions beyond which the speed of decomposition of the perborate, which increases with the concentration of copper ions, becomes too rapid for good bleaching is .00001 to .0001 molar. Slight changes in the concentration of copper ions below or above optimum (which is about .000001 to .00001 molar) will result in a decrease in the bleaching power of the perborate. In practice it was heretofore impossible to obtain this optimum concentration. However, the sequestering agents essential for the compositions of this invention form a metal buffer with the water-soluble copper salt, which maintains the amount of free copper present in the washing medium at a value corresponding to that conducive to maximum bleaching efficiency irrespective of copper additions which are far in excess of that necessary to achieve that maximum value.

- 35 The selection of an organic detergent for use in the compositions of the present invention is not narrowly critical. The detergent may be any water-soluble anionic, or non-ionic compound having detergent properties. Examples of suitable anionic detergents which fall within the scope of the invention include the soaps, such as the water-soluble salts of higher fatty acids or rosin acids such as may be derived from fats, oils and waxes of animal, vegetable or marine origin, e.g. the sodium soaps of tallow, grease, coconut oil, tall oil and mixtures thereof; and the sulfated and sulfonated synthetic detergents, particularly those having about 8 to 26 and preferably about 12 to 22 carbon atoms to the molecule.

- 40 As examples of suitable synthetic anionic detergents there may be cited the higher alkyl mononuclear aromatic sulfonates such as the higher alkyl benzene sulfonates containing from 10 to 16 carbon atoms in the alkyl group, (e.g. the sodium salts of tetrapropyl, hexyl, octyl, nonyl, decyl, dodecyl or ketyl benzene sulfonates) and the higher alkyl toluene, xylene and phenol sulfonates; alkyl naphthalene sulfonates, such as sodium diisopropyl naphthalene sulfonate, ammonium diethyl naphthalene sulfonate, and sodium dinonyl naphthalene sulfonate; sulfated aliphatic alcohols such as sodium dodecyl and hexadecyl sulfates, triethanolamine dodecyl sulfate, and sodium oleyl sulfate; sulfated and sulfonated fatty oils, acids or esters, such as the sodium salts of sulfonated castor oil and sulfated red oil; sulfated hydroxyamides such as sulfated hydroxy-ethyl lauramide; sodium salt of lauryl sulfoacetate; sodium salt of diethyl sulfosuccinate; and the sodium salt of oleyl methyl tauride.

- 45 55 60 65 70 Also included within the ambit of the invention are the sulfuric acid esters of polyhydric alcohols incompletely esterified with higher fatty acids, e.g. coconut oil monoglyceride monosulfate, tallow diglyceride monosulfate; and the hydroxy sulfonated higher fatty acid esters such as the higher fatty acid esters of low molecular weight alkylol sulfonic acids, e.g. oleic acid ester of isethionic acid.

Suitable non-ionic surface active agents are well known to the art and include such agents as the condensation products of alkyl phenols with ethylene oxide, e.g. the reaction product of isooctyl phenol with about 6 to 30 ethylene oxide units; condensation products of alkyl thiophenols with 10 to 15 ethylene oxide units; condensation products of higher fatty alcohols such as tridecyl alcohol with ethylene oxide; condensation products of tall oil with ethylene oxide; ethylene oxide addends of monoesters of hexahydric alcohols and inner ethers thereof such as sorbitan monolaurate, sorbitol mono-oleate and manniitan monopalmitate; the condensation products of polypropylene glycol with ethylene oxide; and the higher fatty acid alkylolamides, e.g. the diethanolamide of coconut oil fatty acids.

The concentration of detergent in the inventive compositions will generally range from 4 to 40% by weight. Substantial amounts of compatible "builder" materials will also be usually present, i.e. of the order of between about 40 to 90% by weight of the detergent composition. Among the builders particularly suitable for the compositions of this invention are water soluble inorganic salts such as sodium sulfate, sodium chloride, sodium tripolyphosphates, sodium pyro- and ortho-phosphates, sodium carbonate and the like.

The perborate bleaching agent preferably employed in the compositions of this invention is sodium perborate and more particularly sodium perborate tetrahydrate, though it will be understood that other perborates can be employed as the bleach. Similarly although copper sulfate is preferably employed as the catalytic agent, any water-soluble copper salt will serve, as for example, the highly soluble nitrate or acetate salts.

Illustrative of the sequestering agents which will form a complex with copper having the essential dissociation constants are methylaminodiacetic acid, aminotriacetic acid and hydroxyethylaminodiacetic acid. These agents form complexes with copper having the following dissociation constants expressed in (logarithms).

Agent:	Dissociation constant of copper complex
Methylaminodiacetic acid	11.09
Aminotriacetic acid	12.68
Hydroxyethylaminodiacetic acid	11.90

Among these sequestering agents the most preferred is aminotriacetic acid (ATA). Substances such as leucine and asparagine, which form copper complexes having dissociation constants within the range indicated for this invention, are not satisfactory because of their instability in the presence of the perborate.

It is to be understood that the pH of the present detergent compositions will normally be in the range from 8-11.5 and that, therefore, the sequestering agents are probably present in the detergent composition as salts. It is to be also understood that strong sequestering agents such as EDTA cannot be effectively employed in the compositions of this invention. This is because EDTA forms a complex with copper having a dissociation constant of 18.5 which is too high, and hence unsatisfactory, for the practice of this invention.

As a consequence of the improved bleaching efficiency at the boil of the perborate in a composition according to the present invention, the content of perborate can be diminished relatively to that of comparable detergent compositions containing strong sequestering agents such as EDTA. The amounts of perborate can be reduced to 5% by weight of the entire composition without experiencing any diminution in bleaching effect in comparison to comparable compositions which contain 10% perborate but lack the instant combination of copper salt and indicated sequestrant. Similarly, compositions containing 10% perborate in combination with 0.2% EDTA by weight without copper salt offer no greater bleaching efficiency than compositions containing 3% perborate, 0.4% ATA and 0.02% by weight anhydrous copper sulfate.

In order to obtain the best results, the amount of copper salt in the detergent composition of this invention must be such that the composition contains from about 30 to about 300 p.p.m. (parts per million) of copper and preferably from 40 to 80 p.p.m. The associated amount of sequestering agent should be such that about 3 to 15 molecules and preferably 10 to 13, thereof, should be present per atom of copper in the detergent composition.

The compositions of this invention can be prepared in any suitable manner such as, e.g., by spray drying the detergent mixture, the mineral salts, and the copper salt, and then adding, by dry mixing, the perborate and the sequestering agent as well as those constituents which could be sensitive to heat, such as perfume.

15 The bleaching efficiency percentage of the compositions of this invention is determined as follows:

Samples of cotton fabric are dyed by means of an oxidizable dye and washed with a bleach-free organic detergent until the complete removal of the excess of dye.

20 These dyed fabrics, having a reflectance on a Hunter colorimeter in the range of 20, are washed with a detergent composition containing an organic detergent and a per-salt, in glass beakers, for the time intervals and at temperatures used in a normal washing at the boil. The persalt partly oxidizes the dye and after washing, the fabric is lighter than at the start.

The reflectance of the fabric is measured by means of a Hunter photometer equipped with a green filter.

25 For convenience the reflectance may be represented as BD before dyeing, BW before washing, and AW after washing. The bleaching efficiency, in percent, is then 100 (AW-BW) divided by (BD-BW).

The following formulations are representative of the compositions of this invention:

30 Water-soluble organic anionic or nonionic detergent (Synthetic detergent, soap or their mixtures) _____ 4 to 40%.

35 Water-soluble inorganic salts ____ 40 to 90%. Perborate, especially sodium ____ 3 to 20%.

Water-soluble copper salt in an amount corresponding in relation to the entire composition of _____ 30 to 300 p.p.m. of Cu (.003% to .03%).

40 Sequestering agent which forms a copper complex having a dissociation constant the common logarithm of which is between -11 and -15, in an amount corresponding for each atom of Cu, of ____ 3 to 15 molecules.

45 Perfume, coloring matter, bleaching agent _____ 0 to 1%.

50 The following examples are given further to illustrate the invention. They are not to be regarded as limiting, the claims being the sole limitation. All amounts and percentages in the specification and in the examples are by weight unless otherwise indicated.

EXAMPLE 1

A "basic" detergent composition is made of the following formulation:

	Percent by weight
Sodium dodecylbenzene sulfonate	22
Sodium tripolyphosphate	30
Monoethanolamide of coconut oil fatty acid	2.5
70 Sodium silicate	7
Magnesium silicate	1
Hydrated sodium perborate	10
Fluorescent dye, perfume, sodium sulfate, and moisture, balance to	100

Washing solutions are prepared by dissolving 12.5 grams or 5 grams per liter of the above basic detergent composition in aqueous washing mediums. Washing is then carried out at the boil and the results noted using each solution. Other washing solutions are prepared in like manner but with the difference that methylaminodiacetic acid, hydroxyethylaminodiacetic acid or aminotriacetic acid sequestrants are separately added to the basic detergent compositions at concentrations of 0.2% by weight of the basic detergent composition.

To separate portions of the respective washing solutions 0, 1, 2, 3, 4 or 5 p.p.m. of copper ions are added, in the form of copper sulfate, and washing is thereupon carried out. The obtained results are indicated in Table I below. In this table maximum bleaching attained for each of the formulas is indicated as well as the length of the bleaching "plateau." This "plateau" is defined as being the interval of concentrations in copper ions (as p.p.m. in the washing solution) for which the maximum bleaching efficiency is not reduced by more than 10% of the maximum value.

Table I

Sequestering agent	Dissociation constant of the copper complex (-log.)	5 g./L. of detergent composition		12.5 g./L. of detergent composition	
		Maximum bleaching efficiency, percent	Length of the bleaching "plateau"	Maximum bleaching efficiency, percent	Length of the bleaching "plateau"
None		89	0.5	51	0.75
Methylaminodiacetic acid	11.1	53	3.8	64.5	5.0
Hydroxyethylaminodiacetic acid	11.9	53	3.8	73	4.9
Aminotriacetic acid	12.8	60	4.7	73	4.6

EXAMPLE 2

To separate portions of the basic detergent formulation indicated in Example 1, there are added 0.2% by weight EDTA or 0.4% ATA and 0.02% anhydrous copper sulfate. To a similar third basic formulation but having a perborate concentration of only 6% by weight there is also added 0.4% ATA and 0.02% of copper sulfate. These formulations are then dissolved as in Example 1, to form washing solutions. The bleaching efficiency of each solution is observed and tabulated in Table II below.

Table II

Compositions:	Bleaching efficiency, percent
Basic composition containing EDTA and 10% perborate	29
Basic composition containing ATA, copper and 10% perborate	45
Basic composition containing ATA, copper and 6% perborate	36

EXAMPLE 3

Another detergent composition of the subject invention is made of the following formulation. It exhibits highly efficient bleaching action when used at the boil.

Sodium tetrapropylbenzene sulfonate 31%.
 Sodium tripolyphosphate 35%.
 Sodium silicate 5.8%.
 Sodium perborate tetrahydrate 10%.
 Copper sulfate in an amount corresponding in relation to the entire composition of 200 p.p.m. of Cu.
 ATA in an amount corresponding for each atom of Cu of 5 molecules.
 Fluorescent dye, perfume, sodium sulfate and moisture Balance to 100%.

EXAMPLE 4

The following formulation also exhibits enhanced bleaching action at the boil.

5	Condensation product of tall oil with 15 moles of ethylene oxide	4%.
	Sodium tripolyphosphate	40%.
	Sodium silicate	7%.
	Sodium perborate tetrahydrate	10%.
10	Copper nitrate in an amount corresponding in relation to the entire composition of	60 p.p.m. of Cu.
15	Methylaminodiacetic acid in an amount corresponding for each atom of Cu of	12 molecules.
15	Fluorescent dye, perfume, sodium sulfate and moisture	Balance to 100%.

EXAMPLE 5

20 Another detergent composition of the subject invention is made of the following formulation. It also exhibits enhanced bleaching action at the boil.

40	Sodium dodecylbenzene sulfonate	8%.
	Sodium salt of sulfated lauryl alcohol	8%.
	Monoethanolamide of coconut oil fatty acid	3%.
	Sodium tripolyphosphate	40%.
45	Sodium perborate tetrahydrate	10%.
45	Sodium silicate	7%.
	Copper acetate in an amount corresponding in relation to the entire composition of	80 p.p.m. of Cu.
50	Hydroxyethylaminodiacetic acid in an amount corresponding for each atom of Cu of	10 molecules.
	Fluorescent dye, perfume, sodium sulfate and moisture	Balance to 100%.

EXAMPLE 6

55 The following formulation also exhibits enhanced bleaching action at the boil.

55	Percent	
60	Condensation product of oleic acid with ethylene oxide in a mole ratio of 1:14.5 respectively	5.70
	Sodium dodecylbenzenesulfonate	2.30
	Sodium stearate	2.00
	Sodium silicate	3.00
	Sodium carboxymethylcellulose	0.90
65	Sodium carbonate	10.00
	Sodium perborate	10.00
	Aminotriacetic acid	0.70
	Copper sulfate hydrate	0.12
70	Fluorescent dye, perfume, sodium sulfate and moisture, balance to	100
	It is to be understood that the invention is not limited to the specific embodiments described above. Various modifications can be made in the process and in the inventive preparations without departing from the spirit or scope of the invention.	

What is claimed is:

1. A stable, substantially dry, perborate-containing detergent composition effective for washing at the boil, consisting essentially of by weight from about 4 to 40% of a member selected from the group consisting of water-soluble, synthetic, non-soap anionic and nonionic organic detergents, from about 3 to about 20% water-soluble inorganic perborate, from about 40 to about 90% water-soluble inorganic alkali metal non-oxidizing builder salts, a water-soluble inorganic copper salt, and a sequestering agent selected from the group consisting of methylaminodiacetic acid, aminotriacetic acid, and hydroxyethylaminodiacetic acid, the copper salt being present in amount sufficient to produce a copper atom concentration of from about 30 to 300 parts per million parts by weight of the detergent composition, and the sequestering agent being present in amount such that 3 to 15 molecules thereof are contained in the detergent composition per atom of copper, said amounts of copper salt and sequestering agent enhancing the bleaching action of the perborate at the boil.

2. A composition according to claim 1 in which the perborate is sodium perborate tetrahydrate and the water-soluble copper salt is copper sulfate.

3. A composition according to claim 1 in which the detergent is a sodium salt of an alkyl aryl sulfonate containing from 10 to 16 carbon atoms in the alkyl group.

4. A composition according to claim 1 in which the concentration of copper is from 40 to 80 parts per million parts by weight of the detergent composition, and the sequestering agent is present in amount such that 10 to 13 molecules thereof are contained in the detergent composition per atom of copper.

5. A stable substantially dry perborate-containing detergent composition effective for washing at the boil, consisting essentially of by weight from 4 to 40% of a sodium salt of a higher alkyl benzene sulfonate containing from 10 to 16 carbon atoms in the alkyl group, from 3 to 20% sodium perborate tetrahydrate, from 40 to 90% water-soluble inorganic alkali metal non-oxidizing builder salts, copper sulfate and a sequestering agent selected from the group consisting of methylaminodiacetic acid, aminotriacetic acid, and hydroxyethylaminodiacetic

acid, the copper salt being present in amount sufficient to produce a copper atom concentration of from 40 to 80 parts per million parts by weight of the detergent composition, and the sequestering agent being present in amount such that 10 to 13 molecules thereof are contained in the detergent composition per atom of copper, said amounts of copper salt and sequestering agent enhancing the bleaching action of the perborate at the boil.

6. A stable substantially dry perborate-containing detergent composition effective for washing at the boil, consisting essentially of by weight about 22% sodium dodecylbenzene sulfonate, about 30% sodium tripolyphosphate, about 2.5% monoethanolamide of coconut oil fatty acid, about 7% sodium silicate, about 1% magnesium silicate, about 10% hydrated sodium perborate, copper sulfate and sequestering agent selected from the group consisting of methylaminodiacetic acid, aminotriacetic acid and hydroxyethylaminodiacetic acid, the copper sulfate being present in amount sufficient to produce a copper atom concentration of from 40 to 80 parts per million parts by weight of the detergent composition, and the sequestering agent being present in amount such that 10 to 13 molecules thereof are contained in the detergent composition per atom of copper, said amounts of copper salt and sequestering agent enhancing the bleaching action of the perborate at the boil.
